UNITED STATES PATENT OFFICE.

FRANK E. WADE, OF CAMDEN, NEW JERSEY, ASSIGNOR TO WADE MANUFACTURING COMPANY, OF CAMDEN, NEW JERSEY, A CORPORATION OF NEW JERSEY.

AUXILIARY SPARKING UNIT FOR SPARK-PLUGS.

1,394,426.

Specification of Letters Patent.

Patented Oct. 18, 1921.

Application filed January 29, 1920. Serial No. 355,004.

To all whom it may concern:

Be it known that I, FRANK E. WADE, a citizen of the United States, residing at Camden, in the county of Camden and State 5 of New Jersey, have invented certain new and useful Improvements in an Auxiliary Sparking Unit for Spark-Plugs, of which the following is a specification.

This invention relates to the subject of 10 sparking devices for internal combustion engines and has particular reference to a novel improvement in spark plugs.

As is well known the fouling of the sparking terminals by oil or carbon soot causes 15 the improper functioning of the spark plug which is not only a source of annoyance to the motorist but is also likely to cause other engine troubles. Various expedients have been heretofore proposed for protecting the 20 sparking terminals, and also providing means for cleaning the same or preventing the accumulation of foreign substances which interfere with the formation of the proper spark. These devices however are 25 more or less complicated and expensive to build, and in many instances involve parts which are relatively frail and frequently become deranged or damaged rendering the entire plug inoperative and worthless.

Accordingly, the present invention has 30 primarily in view the provision of novel means for creating or producing an extremely hot spark which acts with an oxidizing effect, and to this end has in view a device 35 in the form of an attachment adapted to be fitted to any spark plug and greatly intensify the spark, thereby automatically keeping the sparking points free from oil and carbon deposits, and maintaining the 40 efficiency of the plug under all conditions of use.

A further object in addition to the foregoing general object is to provide a device 45 which is simple and easily manufactured, and when applied to a spark plug of standard type, will provide an auxiliary sparking chamber in open communication with the atmosphere, whereby the current supplied to the plug will be compelled to jump a preliminary air gap in an inclosed chamber in order to make its way to the central conductor rod of the plug, thereby greatly intensifying the current supplied to the usual 50 sparking elements and providing in effect a

carbon consuming spark which destroys the 55 accumulation of carbon and prevents fouling in a most effective manner.

With the above and other objects in view which will more readily appear as the nature of the invention is better understood, the 60 same consists in the novel construction, combination and arrangement of parts herein-after more fully described, illustrated and claimed.

A preferred and practical embodiment of 65 the invention is shown in the accompanying drawings, in which:

Figure 1 is an elevation of a spark plug having my improved attachment applied thereto.

Fig. 2 is a vertical sectional view thereof.

Fig. 3 is a detail perspective view of the holding cap for the sparking unit.

Similar reference numerals designate corresponding parts throughout the several figures of the drawings.

In carrying the invention into effect it is intended to provide a device which is susceptible of embodiment in a form that may be readily fitted to standard types of spark 80 plugs, in a simple and expeditious manner. Accordingly, as will be observed from the drawing the reference 1 designates the body of a spark plug having the usual exteriorly threaded attaching portion or shell 2 at one 85 end while the upper end receives the usual gland nut 3 for holding the porcelain sleeve 4 in place. The said porcelain sleeve 4 carries therewith a central conductor rod 5 of the standard design and provided with the 90 sparking end 6 that may be so disposed with reference to the portion 2 of the body of the plug that the spark gap is formed directly between the end of the conductor rod and the body itself without the necessity of utilizing 95 a separate sparking terminal on the shell.

It has been found in practice that the spark passing between the end of the conductor rod 6 and the screw shell is of such magnitude that no separate sparking terminal is 100 required for the best results. Thus, in this respect the invention simplifies the plug by omitting the usual body-carried sparking terminal which eliminates the possibility of fouling from this source.

The novel auxiliary sparking unit which constitutes the distinctive feature of the present invention is designated generally as A.

and includes in its organization, the anchoring or attaching cap previously referred to and shown in detail in Fig. 3. This cap is designated as 6 and is exteriorly threaded as 5 at 7 while its top portion 8 is provided with the threaded opening 9 for receiving the central conductor rod 5, whereby the usual lock nut 10 on the rod 5 may be conveniently utilized to securely hold the cap 6 in position 10 on the upper end of the porcelain sleeve 4 as shown in Fig. 2. This cap may be of any desired shape or form to suit various designs of porcelains, but in all embodiments of the invention it constitutes the important function 15 of providing a relatively large threaded surface for telescopically receiving the insulating hood 11 of the sparking device which carries an independent binding nut and terminal element at its closed end, and 20 by reason of the relatively wide bearing it affords prevents canting of the sleeve with reference to the porcelain.

The said hood 11 is interiorly threaded as at 12 to engage with the threads 7 of the 25 cap 6 and is of relatively long tubular formation to conceal and entirely house the porcelain insulator of the plug. The upper end 13 of the cage or hood is closed to provide a supporting wall for the conductor element 14 which receives the lock nut 15 and binding nut 16 exteriorly of the hood while the portion of said conductor which 30 projects within the hood constitutes a sparking terminal 17 for coöperating with the exposed end 18 of the conductor rod 5. When the insulating hood 11 is applied to the cap 6 a sparking chamber C is provided 35 between the upper end of the cap and the end wall 13 of the hood, and as will be observed from the drawings the said sparking chamber C is in direct communication with the atmosphere through the ports or openings 19 which are preferably formed radially through the side wall of the hood, 40 at a point somewhat above the line of the gap formed between the terminals 17 and 18 to prevent escape of the spark from the cage and thereby meet underwriters' requirements from a safety standpoint. 45

To prevent sparking between the cap 6 and the metallic portion of the body, a washer 20 of suitable insulating material of leather or equivalent material is interposed between the lower end of the hood and the 50 gland nut 3. Thus leakage of current is effectively prevented along the sides of the conductor to the body of the plug.

In practice the auxiliary sparking unit is fitted to the spark plug by first placing 60 the washer 20 in position and then applying the cap 6 to the porcelain of the plug. After the cap is secured by nut 10 the hood may be telescoped over the cap 6 and porcelain so as to bring the terminal 17 of the hood in proper relation to the upper end 18 of

the conductor post 5. The terminal 17 may be of course adjusted with reference to the terminal 18 to provide a proper spark gap, but for certain types of plugs the original setting of the terminal 17 will be sufficient 70 since the terminal will be originally set to meet the standard requirements of the particular type of plug.

When current is supplied to the binding nut 14 in the operation of the engine, it will 75 of course have to jump the spark gap formed between the terminals 17 and 18 in the chamber C which is in communication with the air, and the effect of the spark formed between the said terminals is to supply a current which has been stepped up or transformed to a greater potential or magnitude when it reaches the conductor rod 5, and the result, when the current makes its way from the end 6 of the rod directly to 80 the body or shell 2, is a greatly intensified spark within the combustion chamber of the engine. The temperature of this spark is raised such a degree that it will burn or oxidize the accumulation of carbon which 85 would tend to collect or accumulate on the sparks and shell and thereby insure the firing of the gaseous charge within the cylinder where it would otherwise remain unexploded by reason of the failure of the 90 spark due to carbon or oil deposit.

From the foregoing it will be apparent that the present invention provides a novel auxiliary sparking unit which fulfills all of the objects heretofore set forth, and it is 100 believed that the construction, operation and advantages of the improvement will be readily apparent to those skilled in the art without further description.

I claim:

1. A sparking unit for spark plugs, including in combination with the central conductor and the insulator surrounding the same, a tubular hood closed at one end and open at the other to thereby telescopically fit over the insulator, a wire binding terminal carried by the hood, and a metallic member engaging with the hood and conductor rod to prevent displacement of the hood.

2. A sparking unit for spark plugs, including in combination with the central conductor and the insulator surrounding the same, a tubular hood closed at one end and open at the other to thereby telescopically fit over the insulator and having air ports, 110 a wire binding terminal carried by the hood, and interior means for holding the hood on the insulator consisting of a member having its periphery engaging with the hood and provided with a central opening for receiving the conductor rod to thereby hold the hood on the insulator.

3. A sparking unit for spark plugs, including in combination with the insulator and central conductor rod, a tubular insulat-

ing member adapted to telescopically fit over and house the entire insulator of the plug, a wire terminal carried by said tubular member and adapted to coöperate with the 5 conductor rod to form an auxiliary spark gap, and an element for locking the tubular member to the conductor rod, said element having its peripheral edge portion engaging with the interior of the tubular member and

provided with a central opening for receiving the central conductor rod. 10

In testimony whereof I hereunto affix my signature in the presence of two witnesses.

FRANK E. WADE.
